PROCESS OF REMOVING SOAPS FROM ASPHALTIC STILL BOTTOMS AND PURIFYING THE SAME

Hasson T. Terrell, Edward M. Hughes, and Philip L. Carter, Chester, Pa., assignors to Sun Oil Company, Philadelphia, Pa., a corporation of New Jersey

Application April 15, 1935, Serial No. 16,270

2 Claims. (Cl. 87—9)

The present invention relates to a process for producing cutting oil and more particularly to a process for producing cutting oil comprising a blend of lubricating oil and soaps of petroleum naphthenic acids, and to the method of producing such soaps.

When distilling lubricating oils from a topped residue, or mazoot, derived from a coastal naphthenic or asphaltic base crude which has been treated with caustic soda before distillation, there is produced an asphaltic still bottom which contains soaps of petroleum naphthenic acids in considerable quantities. Such a process is described and claimed in the patent to Arthur E. Pew, Jr., No. 1,761,153, issued June 3, 1930. In the process outlined above and described and claimed in the patent, the topped crude or mazoot is treated with caustic soda before distillation for the purpose of converting any contained petroleum naphthenic acids into their corresponding soaps or sodium salts. This procedure is followed in order that the distillates thereby produced will not contain the petroleum naphthenic acids, thereby rendering unnecessary excessive acid treatment and neutralization of the distillates produced.

The petroleum naphthenic acids, which are naturally contained in coastal and other similar crudes, have boiling points which approximate those of the lubricating fractions in such crudes. It is therefore impossible to avoid distilling off such petroleum naphthenic acids, if the topped crudes or mazoots are distilled without preliminary treatment. The preliminary treatment with caustic soda solution, however, transforms any contained petroleum naphthenic acids into their corresponding soaps or sodium salts, which soaps have boiling points much higher than any of the lubricating fractions distillable from the mazoot below cracking temperatures.

Heretofore cutting oils have been produced by extracting these so-called petroleum naphthenic acids either from distillates, where the mazoot has not been treated with caustic soda, or from the asphaltic bottoms where caustic soda treatment has been used and by expensive and difficult methods such, for instance, as pressure setting methods, as described in the patent to Harry F. Angstadt, No. 1,931,880, issued October 24, 1933, or the patent to Gellert Alleman, No.

1,694,463, issued November 11, 1928, wherein the oils or asphaltic bottoms containing the soaps are converted by the addition of water into an emulsion, the emulsion heated under super-atmospheric pressure to a temperature above the boiling point of water and the soap solution settled from the asphalt; or the lubricating distillates containing the fatty acids are treated with sulphuric acid, the precipitate drawn off and the remaining body of naphthenic acid containing oil treated with an alkali to form an emulsion. The emulsion so formed is then settled, and the soap and water layer withdrawn, leaving a soap-free mineral lubricating oil. To the soaps so extracted there is added a small proportion approximating about 30% of a light mineral oil to form the desired cutting oils.

We have discovered that such cumbersome methods may be dispensed with entirely, and a cutting oil containing naphthenic soaps may be obtained in a much simpler manner without the difficulty of breaking up recalcitrant emulsions.

It is therefore an object of the present invention to remove the naphthenic bodies from asphaltic residues containing the same and to manufacture a cutting oil from the same without reducing the original starting material, or any of the intermediate products, to emulsion form.

A better understanding of the invention will be had by reference to the accompanying drawing which is a diagrammatic representation of one type of equipment in which the present invention may be carried out.

Referring now to the drawing:

A, B, and C represent agitators such as are usually used in petroleum refineries for the acid treatment and neutralization of lubricating oils.

D represents a distillation unit wherein the distilland is heated by means of the latent heat of condensation of mercury vapor. Such an apparatus is described and claimed in the patent to Arthur E. Pew, Jr., No. 1,761,151, issued June 3, 1930.

E also represents an agitator of the same type as A, B, and C.

The balance of the equipment shown in the drawing consists of storage tanks, run down tanks, condensers, coolers, and heaters such as form a part of the equipment in any petroleum refinery.

Referring now more particularly to the drawing, the soap-containing asphalt bottoms such as derived from a distillation process, as described and claimed in Pew Patent 1,761,153, are admitted to the process through line 1 under a pressure imposed by pump 2. These bottoms are fed to a manifold line 3, having valved branches 4, 5, and 6 leading to each of the agitators A, B, and C, respectively. Sulphuric acid is admitted to the process from an acid ball, or any suitable source, through valved line 7 to manifold 8 from which it is fed by means of valved branches 9, 10, and 11 to each of agitators A, B, and C, respectively. The agitators A, B, and C are each provided with valved outlets 12, 13, and 14 leading to a manifold line 15 in which is placed a pump 16 for pumping the material from the agitators. Leading into the manifold 15 is a valved line 17 containing a pump 18 which takes suction on a lubricating oil storage tank 19. The line 18 leads through a heater or heat exchanger 20 and thence to the distillation plant D. There is also provided a tank 21, having a valved inlet 22, and a valved outlet 23 containing pump 24. This tank may be used as storage for a portion or all of the material flowing from the agitators A, B, and C, and tank 19 toward the distillation unit D.

The distillation unit D consists of a vaporizer 25 having upper and lower portions separated by a flat plate 26. The material to be distilled passes into the vaporizer 25 from line 27 leading from the heater 20. A pool of the material is maintained at one end of the vaporizer 25 by means of the weir 28. The material to be distilled overflows this weir and flows in a thin film downwardly over the plate 26, being heated during its travel by means of the latent heat of condensation of mercury vapor which is admitted to the lower portion of the vaporizer 25 through line 29, the liquid mercury formed by the condensation being withdrawn through line 30 and returned to the mercury boiler (not shown). Any material which is unvaporized in the vaporizer 25 flows out through line 31 which connects with the inlet end of the next vaporizer in series. For the present purposes, there would ordinarily be from 6 to 10 of these vaporizers in series. However, one only is shown in the drawing for the purpose of simplicity.

50 The vapors generated within the vaporizer 25 are withdrawn through lines 32 which lead to a vapor manifold 33 from which in turn lines 34 lead to a distillation tower of the bubble plate type designated 35. Within the bubble tower 35 above the vapor inlets 34, there is placed an annular pan 36 and a series of bubble trays 37, the pan 36 providing a throat to permit the upward passage of uncondensed vapors. That section of the tower below the pan 36 also contains several 55 bubble plates to aid in the proper separation of liquid and vapor within that section of the tower. That portion of the vapor which is condensed below the pan 36 is drawn off from the bottom of the tower through line 38 and is returned to the inlet end of the vaporizer. Those vapors which pass up through the throat in pan 36 are fractionally condensed, by means of reflux liquid added to the top of the tower, and run down over the plates in the tower and are withdrawn through line 39 and cooler 40 to run down tank 41, whence they are periodically withdrawn through valved line 42, containing pump 43, and delivered to tank 44. The vapors which are uncondensed in the tower 35 pass overhead through line 45 to a condenser 46, whence they pass to

reflux tank 47. The condensed and cooled liquid in tank 47 is withdrawn through valved line 48 by means of pump 49 and is returned to the top of the tower 35 to aid in the condensation of the vapors passing therethrough. The temperature within tower 35, and therefore the rate of cooling, is maintained such as to preclude the passing overhead and cooling of more vapors than are necessary to form the required quantity of reflux. If, however, a superfluous amount of 10 reflux accumulates in tank 47 it is withdrawn to storage through valved line 48 by means of pump 50. From the top of reflux tank 47 there is a valved line 51 which leads to vacuum producing equipment, since it is desirable, if not necessary, 15 to maintain the various stills in the series D under absolute pressures which vary from still to still, but are all very low.

Leading from the bottom of tank 44 there is a valved line 52 containing pump 53. This line 20 leads to and through a heater or heat exchanger 54. From the heat exchanger a line 55 leads to the top of agitator E. Line 56, for the conveyance of caustic soda solution, also leads to the top of agitator E, as does valved line 57 leading from oil storage tank 58; the oil being forced from this tank to the agitator by means of pump 59. A valved line 60 leads to the bottom of the agitator E for the admission of compressed air, 25 for the purpose of blowing the material within 30 agitator E. The bottom of the agitator E is provided with a valved outlet 61 containing pump 62 for the purpose of forcing the material from agitator E to storage tank 63.

The apparatus just described is used as follows in carrying out the present process:

Asphaltic products, containing soaps of naphthenic acids, from a lubricating oil distillation process are admitted through line 1 and any of its branch lines 4, 5, and 6 to one or all of the agitators A, B, and C. These bottoms are preferably heated to a temperature varying between 300° and 500° F. When a sufficient quantity of bottoms has been admitted to one or all of the agitators, depending on whether the first portion of 45 the process is being run, as a batch process or a continuous one. 66° Bé. sulphuric acid (96-98% H₂SO₄) is added through lines 9, 10, or 11. The acid so admitted is in a quantity not more than sufficient (practically a quantity not 50 quite sufficient) to completely convert the contained soaps to their corresponding petroleum naphthenic acids. This is quite necessary, since an excess of sulphuric acid would have an exceedingly deleterious corrosive action on the succeeding equipment. After the proper quantity of acid has been added, the contents are agitated until the acid has completely reacted with the contained soaps, converting them to their corresponding acids, and forming sodium sulphate as 55 a reaction product. After the reaction is complete, the acidified bottoms are withdrawn through lines 12, 13, or 14 to line 15 by means of pump 16. To the line 16 is also added 5-15% of a lubricating oil distillate having, for example, 60 a flash of 370-385° F. a fire of 430-445° F., and a Saybolt viscosity at 100° F., of 500-530 seconds. This oil is preferably heated to about 400° F., or the approximate temperature of the acidified bottoms. The mixture so produced is then passed 65 either to tank 21 or directly to the distillation equipment D.

As explained in the first part of the present specification, the soaps contained in the bottoms are converted to their corresponding acids. Even 75

though the acids have a much lower boiling point than the asphalt containing them and are therefore distillable from the bottoms, whereas the soaps have boiling points much too high to be distilled without cracking, the acids are not readily distillable without the admixture of an oil such as, or similar to, that just described, since the asphalt exerts a sufficiently high partial pressure effect to make it extremely difficult to distill the acids below cracking temperature without also distilling off a portion of the asphalts, or at least carrying off a portion of the asphalt in entrainment. However, by the addition of from 5 to 15% of a lubricating oil as above described, it is possible to readily distill these acids without cracking, due to the fact that the added oil exerts a partial pressure effect, and is much lower boiling than the asphaltic constituents or the acids being distilled. Since a certain proportion of lubricating oil is requisite in the final product, the addition of oil at this stage imposes only a slight added burden on the plant, which burden is more than offset by the added advantages obtained. In certain cases the asphaltic bottoms fed to the process will contain some undistilled lubricating oils, in which case it will be unnecessary to add any oil as above described, since the oil remaining in the asphalts will exert sufficient partial pressure effect to render the acids distillable at not prohibitively high temperatures.

The acidified bottoms and oil from line 15 or tank 21, as the case may be, are heated in heater or heat exchanger 20 to a temperature approximating 450-525° F., unless they are withdrawn from the acidification step at about that temperature. The preheated mixture is then passed through line 27 to the first vaporizer 25 in the series wherein the material is heated under a vacuum to drive off a portion of the oil and acids. The distill and unvaporized in this vaporizer is then passed, by means of line 31, to the next vaporizer in series. The vapors generated within the vaporizers 25 are withdrawn through risers 32, manifolds 33, and lines 34 to the towers 35, within the lower portion of which a small proportion of the vapors are condensed and returned by means of lines 38 to the inlet end of the vaporizer wherein they were generated, the remaining portion passing up through the throats in pans 36 and being in the major part condensed by contact with the reflux liquid flowing downwardly over trays 37. The remaining portion passes through lines 45 and condensers and coolers 46 to the reflux lines 47, the condensate within the reflux tank being withdrawn and returned through lines 48 to the tops of towers 35. The amount of vapors passed overhead is controlled by the temperatures in the towers so as to provide, on condensation and cooling, just sufficient reflux to condense the desired side streams within the towers 35. The side streams, which are withdrawn through lines 39 from pans 36, are the desired acids and oil distilled therewith and are passed through coolers 40 to run down tanks 41.

In the production of the usual grade of cutting oil all of the distilled acids are pumped from the run down tank 41 to a single storage tank 44. However, in certain cases it may be desirable to segregate the various fractions distilled and classify them as to viscosity or saponification number for various other uses, or for making various grades of cutting or emulsifiable oils.

Generally the best results are obtained by

maintaining the various vaporizers 25 and towers 35 under increasingly higher vacuums or, properly speaking, under progressively lower absolute pressures from the inlet end to the outlet. These absolute pressures will vary from say 30 mm. mercury at the inlet to as low a pressure as possible for the last still in the series. These pressures, of course, will vary greatly depending upon the material being distilled, its derivation, and the amount of lubricating oil remaining therein, or the amount of lubricating oil added after acidification of the bottoms.

As a specific example, the following inlet temperatures and absolute pressures will serve to demonstrate the method of distilling wherein a battery of seven stills was employed.

Still No. 1	570° F.	18-14 mm.					
Still No. 2	605° F.	13-11 mm.					
Still No. 3	630° F.	11-8 mm.					
Still No. 4	650° F.	10-8 mm.					
Still No. 5	665° F.	10-8 mm.					
Still No. 6	675° F.	9-6 mm.					
Still No. 7	680° F.	8-6 mm.					

The amount of acids distilled from the bottoms as a whole, or obtained in each cut, will, of course, vary slightly depending upon the crude from which the starting material was derived. The following, however, will serve as an example:

Still numbers	No. 1	No. 2	No. 3	No. 4	No. 5	No. 6	No. 7	
Tests:								
Say. vis. at 210° F.	45	69	95	119	112	134	157	35
Saponification No.	55.9	43.3	33.1	27.3	28.5	24.7	19.5	

When the above acids were combined, the total showed a viscosity of 75 seconds Saybolt at 210° F., and a Saponification No. of 40.6.

The composite of these cuts is withdrawn from the tank 44 through line 52 by means of pump 53, and is pumped through a heater 54 and line 55 to the agitator E. The proper quantity of caustic soda solution of 35°-41° Bé. (about 29-36% NaOH) is then added through line 56. Agitation is then carried out by means of air admitted through line 60, or other suitable means, until the acids are completely saponified. The amount of sodium hydroxide added, and its strength, will vary depending upon the water content of the acids, the water content desired in the finished material, and the saponification value of the acids or mixture of acids and oil. Generally it has been found that with a composite such as illustrated above, 38° Bé. caustic soda in the proper proportions gives a product having the required characteristics. It is usually advisable to use a slight excess of caustic soda solution, so that the finished product will be very slightly on the alkaline side. If the saponified mixture contains too much water, it is blown with air to remove the excess water content.

After saponification, a light mineral lubricating oil having a Saybolt viscosity of 100-115 seconds at 100° F. is added in amounts varying from 20% to 50%, depending upon the amount of soaps desirable in the finished product, the viscosity desired in the finished product, and the emulsifying qualities required. This oil is added by means of valved line 57, the oil being drawn from tank 58 and pumped by means of pump 59.

The finished cutting oil (which is an emulsoid or dispersoid system itself before the addition of water) will have approximately the following

characteristics, depending upon the amount of oil added in both cases:

5	30% Light oil 70% soap and heavy oil	40% light oil 60% soap and heavy oil
A. P. I. Gravity.....	16.3°	17.2°
Flash ° F.....	240	330

Alkalinity % NaOH.....	0.08	0.07
Sap. value.....	22	19
Sap. equivalent mg. KOH.....		

What we claim and desire to protect by Letters Patent is as follows:

1. The process of producing a blend of lubricating oil and naphthenic acid soaps from asphaltic bottoms containing naphthenic acid soaps produced in the distillation of naphthenic base oil in the presence of an alkali, which comprises adding to said bottoms a mineral acid, thereby effecting the acidification of soaps, and adding also a sufficient quantity of lubricating oil of lower

boiling point than the asphaltic bottoms to enable the hereinafter recited distillation to be effected without substantial cracking of the distillate, subjecting the resultant emulsion of asphalt, oil and naphthenic acids to distillation to vaporize the acids and oil, condensing the acid-oil vapors, and adding to the condensate an alkali adapted to convert the contained acids to soaps and form a mineral oil and soap emulsion.

2. The process of producing a blend of lubricating oil and naphthenic acid soaps from asphaltic bottoms containing naphthenic acid soaps produced in the distillation of naphthenic base oil in the presence of an alkali, which comprises adding to said bottoms a mineral acid in an amount not quite sufficient to completely acidify the soaps and adding also lubricating oil, subjecting the resultant emulsion of asphalt, oil and naphthenic acids to distillation to vaporize the acids and oil, condensing the acid-oil vapors, and adding to the condensate an alkali adapted to convert the contained acids to soaps and form a mineral oil and soap emulsion.
